[57] CLAIM

The ornamental design for a bottle, as shown and described.

DESCRIPTION

FIG. 1 is a front elevational view of a bottle showing my new design;

FIG. 2 is a rear elevation view;

FIG. 3 is a left side elevational view;

FIG. 4 is a right side elevation view;

FIG. 5 is a bottom plan view;

FIG. 6 is a top plan view; and,

FIG. 7 is a perspective view of the bottle showing my new design.

The broken lines showing a bottle cap in FIGS. 1, 2, 3, 4 and 7 are for illustrative purposes only and do not form part of the claimed design.
